UNITED STATES PATENT OFFICE.

EDWARD BURNS, OF COVINGTON, LOUISIANA.

WATER-CYCLE APPLIANCE.

1,160,257.

Specification of Letters Patent.

Patented Nov. 16, 1915.

Application filed July 13, 1914. Serial No. 850,732.

To all whom it may concern:

Be it known that I, EDWARD BURNS, a citizen of the United States of America, residing at Covington, parish of St. Tammany 5 and State of Louisiana, have invented certain new and useful Improvements in Water-Cycle Appliances, of which the following is a specification, reference being had therein to the accompanying drawing.

10 This invention relates to a water cycle appliance, and has for its object the production of a simple and efficient means for the operation of ferry boats and the like adapted to ply across the river, stream or other 15 body of water, and has for its object the production of a simple and efficient means for operating the water cycle appliance.

Another object of the invention is the production of a simple and efficient device 20 whereby the craft used in connection with the water cycle appliance may be supported upon or as nearly upon the surface as possible in order to avoid the resistance of the water upon the craft while moving within 25 the water over which the device is adapted to pass.

With these and other objects in view this invention consists of certain novel combinations, constructions, and arrangements 30 of parts as will be hereinafter fully described and claimed.

In the accompanying drawings:—Figure 1 is a perspective view of the device in operation. Fig. 2 is a top plan view of the 35 craft or boat. Fig. 3 is a central longitudinal section through the device illustrated in Fig. 2. Fig. 4 is a transverse section taken on line 4—4, of Fig. 3, the engine being eliminated therefrom. Fig. 5 is a top plan 40 view of the winding drum. Fig. 6 is a side elevation of the winding drum. Fig. 7 is a perspective view of one of the guiding tubes through which one of the winding cables is 45 adapted to pass.

By referring to the drawings it will be seen that 1 designates the body of the craft or boat which is preferably formed of an elongated body pointed at both ends, although it should be understood that any 50 desired shape craft or boat may be employed for accomplishing the desired purpose. The boat 1, however, is preferably provided with a flat bottom in order to float upon the top of the surface of the water as 55 nearly as possible, and thereby avoid the great amount of resistance which would

take place against the craft, providing the same was submerged for any great depth within the water. It should be understood that any form of craft may be employed, 60 large or small, for the operating mechanism without departing from the spirit of the invention.

A plurality of supporting brackets 2 are mounted within the boat 1 and upon these 65 supporting brackets 2 is mounted a central supporting shaft 3, which central supporting shaft 3 carries a drum frame 4 as is illustrated in Figs. 2 and 5. This drum frame 70 4 comprises a plurality of parallel plates and between these parallel plates are carried rollers 5, which rollers may be independently rotated upon the drum frame 4 relative to the supporting shaft 3. The supporting shaft 3 carries a driving pulley 6, which 75 driving pulley carries a driving belt 7 passing from an engine 8, and thereby imparting power to the supporting shaft 3 for the purpose of operating the drum frame 4.

A cable guiding tube 9 is carried at each 80 end of the boat 1, and these cable guiding tubes 9 are supported upon supporting brackets 10 of suitable construction. The cable guiding tubes 9 pass from a point adjacent the drum frame 4 and through the 85 respective ends of the boat 1 as is clearly illustrated in Fig. 3. These tubes 9 are inclined toward the respective ends of the boat from the drum frame 4 as is clearly 90 illustrated in Fig. 3 so as to cause the cable 11 which passes therethrough to hang under the surface of the water as illustrated in Fig. 1 as the drum 4 winds the cable for the purpose of pulling the boat from one shore of the body of water to the other. 95

The cable 11 is attached at its respective ends to stakes 12 placed upon opposite shores of the body of water, and this cable passes through the tubes 9 carried by the boat 1 and then passes around the rollers 5 carried 100 by the drum frame 4 for the purpose of being wound over or under the rollers 5 as the drum frame 4 rotates upon the supporting shaft 3. It should be understood that these cables do not wind around the drums individually, but pass from one drum to the other and form a substantially loop-like wind to allow the drum frame 4 to assume the different positions illustrated in Fig. 3 as the supporting shaft 3 is rotated. 105

It should be understood that as the drum frame 4 is being rotated in the direction as 110

- indicated by the arrow, the cable 11 will be drawn or wound over the rollers 5 of the drum frame 4. It should be understood that the tubes 9 pass down an incline toward the 5 respective ends of the boat 1 and terminate short of the drum frame 4 so as to allow the cable to pass easily over the drum frame when the frame is in a horizontal position such as illustrated in dotted lines in Fig. 3.
- 10 It should be understood that the present device may be employed in connection with canal boats and the like, if it should be so desired for the purpose of towing without departing from the spirit of the invention.
- 15 It should be understood that the cable which is carried by the boat will normally lie under the surface of the water so as not to interfere with navigation upon the stream over which the boat may be traveling. This 20 construction is clearly illustrated in Fig. 1.

Copies of this patent may be obtained for five cents each, by addressing the "Commissioner of Patents, Washington, D. C."

Having thus described the invention what is claimed as new is:—

In a device of the class described, the combination with a boat, a supporting shaft carried thereby, a drum frame carried by said shaft, a drum carried by each end of said drum frame, a guiding tube carried by each end of said boat, a cable passing through said guiding tube and wound over said drum, said guiding tubes extending at an angle to the bottom of said boat for causing the said tubes to be inclined from the respective ends of said boat, and supporting means for said guiding tubes.

In testimony whereof I hereunto affix my signature in presence of two witnesses.

EDWARD BURNS.
